UNITED STATES PATENT OFFICE.

WADE HAMPTON SAUNDERS, OF ROANOKE, VIRGINIA.

BIRD-CALL.

1,034,307.

Specification of Letters Patent. Patented July 30, 1912.

Application filed April 29, 1912. Serial No. 693,996.

To all whom it may concern:

Be it known that I, WADE H. SAUNDERS, a citizen of the United States, residing at Roanoke, in the county of Roanoke and State 5 of Virginia, have invented a new and useful Bird-Call; and I do hereby declare the following to be a full, clear, and exact description of the invention, such as will enable others skilled in the art to which it appertains to make and use the same.

This invention belongs to the art of acoustics, and it particularly relates to a new and useful bird call, and especially to one adapted for imitating the yelping of wild turkeys.

In carrying out the invention, it is the purpose to provide a tone tube, constructed of a section of corn cob, in the smaller end of which a stylus needle, constructed of any suitable wood or other fiber, for instance, 20 such as ash or the like. This stylus needle terminates in a large head, the outer lower surface of which is substantially spherical. The body of the stylus needle upon two of its sides slightly beyond the tone tube, gradually merges or blends into a thin flat blade, which terminates abruptly and short of the head. Adapted to be used in conjunction with the combination stylus needle and tone tube is a thin flat piece of slate or the like. 25 The stylus needle when pushed across the slate with light grating strokes, with the flat sides of the blade at right angles to the plane of the strokes, readily vibrates, and the operator by holding the slate with its 30 edge on his thigh and forming a cup or hollow about one side of the slate, and alternately opening the hollow and placing and removing the thumb of his right hand over the tube, he may imitate various notes of 35 wild turkeys and the like.

The invention comprises further features and combination of parts, as hereinafter set forth, shown in the drawings and claimed.

In the drawings:—Figure 1 is a view 45 showing the application and the use of the improved bird call. Fig. 2 is a perspective view of the tone tube with its stylus needle. Fig. 3 is a sectional view through the tone tube showing the stylus needle secured there- 50 in. Fig. 4 is a detail view of the slate.

Referring to the drawings 1 designates the tone tube or arm, which is constructed of a section of a corn cob, the pith of which is removed, thus rendering the section of corn 55 cob hollow, as shown at 2. The tone tube is of a tapering contour as shown, and se-

cured in the smaller end thereof, by friction or some suitable adhesive material or other means is the body 3 of the stylus needle. The body 3 slightly beyond the smaller end 60 of the tone tube gradually tapers upon opposite portions thereof into a thin flat blade 4, which terminates short of an enlarged head 5 at the end of the blade.

In using the tube and needle, the spherical 65 surface 6 of the head is brought in frictional contact with the slate plate 7, with the needle and tube at a slight angle thereto, as shown in Fig. 1, which operation will cause the blade 4 to vibrate, and the tube will act as a 70 sounding drum or board, and by removing and placing one's thumb over the bell portion of the tube, the tone of the notes emanating therefrom may be varied. The slate plate 7 is adapted to be held in the left hand 75 of the operator, the hand forming a hollow on one side of the plate, with one edge of the plate engaging the thigh. By alternately raising and lowering the plate with relation to the thigh, the hollow formed on one side 80 of the plate may be gradually and alternately opened and closed, thereby also varying the tone of the notes of wild turkey and the like. The wall of the tone tube is comparatively thin, and at the bell portion of 85 the tube it gradually tapers to a fine peripheral edge, thus enabling the operator in producing true imitations of notes of wild turkeys.

This improved bird-call is especially 90 adapted for use by hunters.

From the foregoing it will be noted there has been devised a simple and efficient improved bird-call, and one which has been 95 found by experience to be desirable and practical.

The invention having been set forth, what is claimed as new and useful is:—

1. A turkey call, comprising a tone tube, 100 a stylus needle comprising a body portion, which gradually tapers into a substantially thin blade having a head at its end, the lower surface of which is spherical in contour, the stylus needle adapted to be held 105 against a piece of slate or the like in moving frictional contact, causing a vibration of the blade in imitation of the note of the wild turkey.

2. A turkey call, comprising a hollow tone 110 tube constructed of a section of a corn cob terminating at one end in a blade stylus needle having a spherical head, adapted to

be held against a piece of slate or the like held in the hollow of one's hand and against one's thigh in moving frictional contact, causing a vibration of the blade stylus needle, in imitation of the note of the wild turkey.

In testimony whereof I have signed my

name to this specification in the presence of two subscribing witnesses.

WADE HAMPTON SAUNDERS.
